(57) **CLAIM**

The ornamental design for a portion of a cabinet shelf divider, as shown and described.

DESCRIPTION

FIG. 1 is a top perspective view of a portion of a cabinet shelf divider;

FIG. 2 is a right side elevation view of the divider portion of FIG. 1;

FIG. 3 is a front elevation view of the divider portion of FIG. 1;

FIG. 4 is a back elevation view of the divider portion of FIG. 1; and,

FIG. 5 is a bottom elevation view of the divider portion of FIG. 1.

The dashed broken lines in FIGS. 1-5 represent environmental subject matter and form no part of the claimed invention. A top elevation view of the divider portion of FIG. 1 is fully disclosed in the top perspective view of FIG. 1. A left side elevation view of the divider portion of FIG. 1 is a mirror image of the claimed subject matter of the right side elevation view of FIG. 2.
